DEVICE FOR ALIGNING FEED OF PAPER SHEETS IN PRINTING MACHINES

George Babiez, Chicago, Ill.

Application July 5, 1951, Serial No. 235,241

3 Claims. (Cl. 271—49)

1

The present invention relates to devices for properly alining or correcting the feed of paper sheets in printing machines, and has for its main object the provision of a suitable device whereby the paper sheets may be properly adjusted so that the same may be fed towards and into the printing rollers upon a uniform line relative to the transverse plane through the printing rollers.

While in my co-pending application, Serial No. 73,158, filed January 27, 1949, which has matured in Patent No. 2,604,322, I have disclosed a device for adjusting the feed of paper sheets longitudinally with relation to the direction of the shifting of the paper sheets towards the printing rollers, or in a transverse relation with the printing rollers, the present device has for its object the adjustment of the paper sheets transversely with relation to the direction of the shifting of the paper sheets towards the printing rollers, or in a longitudinal relation with the printing rollers.

Another object of the present invention is the provision of a guide in a parallel relation with the conveyor upon which the paper sheets are carried toward the printing roller, with means causing one side edge of a paper sheet as the same is shifted towards the printing rollers to come in contact with the said guide so that the paper sheet may be fed upon a straight line which is co-incidental with the sides of the paper sheets.

A still further object of the present invention is the provision of a pair of wheels, coacting with the guide aforesaid, and in a biased relation therewith, and engaging the paper sheet as the same is shifted upon a conveyor towards the printing rollers, for forcing one side edge of a paper sheet to come in contact with the guide so that the paper may be fed to the printing rollers upon a uniform straight line.

Another object of the present invention is the provision of means for regulating the pressure of the said wheels upon the paper sheet engaged thereby so as to render the device efficient and operable relative to the various weights and thicknesses of the paper sheets.

A still further object of the present invention is the provision of a plurality of resilient feathers pressing against the opposite side edge of the paper for shifting the paper towards said guide whereby the opposite side edge of the paper may come in contact with the said guide so that the paper sheets may be shifted and fed towards the printing rollers upon a uniform line, and which said feathers may act as auxiliary means to said wheels, or wholly independently thereof.

2

With the above general objects in view and others that will appear as the invention is better understood, the same consists in the novel construction, combination and arrangement of parts hereinafter more fully described, illustrated in the accompanying drawings and pointed out in the appended claims.

In the drawings forming a part of this application and in which like designating characters refer to corresponding parts throughout the several views;

Fig. 1 is a plan elevational view of the track upon which the paper sheets are carried towards the printing rollers, with the present device in an operative position therewith;

Fig. 2 is an enlarged side elevational view of the guide and a pair of wheels in a biased or oblique relation therewith which engage the paper as the same is fed towards the printing rollers, for forcing one of the side edges of the paper sheet to come in contact with the guide, the view having been taken substantially on line 2—2 of Fig. 1;

Fig. 3 is a view transversely of the guide, on line 3—3 of Fig. 1 illustrating the rear elevational view of the paper engaging wheels;

Fig. 4 is an enlarged side elevational view of another guide supporting a plurality of feathers for contacting the opposite side edge of the paper as the same is fed towards the printing rollers for shifting the paper sheet away from said guide and the feathers and towards the opposite first hereinabove mentioned guide, the view having been taken on line 4—4 of Fig. 1; and

Fig. 5 is a cross sectional view taken on line 5—5 of Fig. 1.

Referring in detail to the present drawings there is shown a frame, including a pair of frame bars 10 in a parallel mutual relation. One end of said frame bars 10 supports bearings 11, within which shaft 12 is journaled, the latter supporting printing roller 13. Another printing roller, not shown, is in contact with said roller 13 and disposed therebelow. Mounted upon said frame bars 10 in a downwardly depending relation is a plurality of rods 14, in a transverse relation with the frame, and in a parallel relation with the printing rollers. Rod 14, nearest disposed to the printing rollers has a pair of sprocket wheels, including integrally formed collars 15, journaled thereon for supporting the front ends of a pair of endless conveyor chains 16, the latter being provided with the usual pairs of pins 17, which engage the rear edges of paper sheets

18 for carrying the same towards the printing rollers as said chains 16 shift.

Disposed outwardly of each conveyor chain 16 is a guide, which is generally indicated by numeral 19 in Fig. 1, and which includes horizontal plate 20 and a vertical guard 21, integrally formed therewith. Vertical guard 21 of each guide 19 is farthest removed from the adjacent conveyor chain 16. Horizontal plates 20 of said guides 19 are substantially in a co-planar relation with the upper level of conveyor chains 16, so that the paper sheets carried towards the printing rollers rest upon said conveyor chains 16 as well as upon horizontal plates 20. Upper plate 20 as viewed in Fig. 1 is slightly on a lower plane than the lower plate 20, for the reason which will be later apparent.

Mounted upon said plates 20, and downwardly depending therefrom are brackets 22, the free ends of which are recessed for receiving therewithin said rods 14. By virtue of this arrangement guides 19 may be shifted to or away from each other for substantially conforming the space therebetween to the width of the paper sheets. Passed laterally of said brackets 22 are thumbscrews 23 for engaging rods 14 and thereby for maintaining guides 19 in their adjusted position.

As an additional means for adjusting the guides 19 there is shown in Fig. 1 an oblong slotted plate 24, soldered or otherwise rigidly affixed to the underface of plate 20. Said plate 24 is supported upon plate 25 which extends from frame 10. By means of bolt and wing nut fastener 26 the two plates 24 and 25 are interlocked to maintain them in a mutual adjusted relation, and thereby for rigidly maintaining guide 19 in an adjusted position with relation to the adjacent frame 10.

One of said plates 20 is provided with an oblong slot 27. Portion of wheel 28 enters said slot, so that a point of its periphery is on a plane coincident with the upper face of plate 20. Said wheel 28 is supported upon shaft 29, which is journaled in bearing 30. The latter is affixed to the outer face of guard 21 and downwardly depends therefrom, as is seen in Fig. 2. Said shaft 29 by universal joint 31 connects with shaft 32, which has sprocket wheel 33 keyed thereto. Said sprocket wheel 33 has a hub collar 34 integrally formed therewith at both sides thereof. Said collar contacts with bearing 35 extending from plate 36, the latter rigidly supported by frame bar 10. Said shaft 32 is supported within said bearing 35 for rotary movement therewithin. Collar 37 integrally formed with shaft 29 normally contacts with the adjacent face of bearing 30, preventing said shaft 29 from further shifting in the direction of bearing 30.

Sprocket chain 38 is passed over sprocket wheel 33. Motive power is imparted to chain 38 for rotating sprocket wheel 33 and through it shafts 32 and 29 for imparting a rotary movement to wheel 28.

It is observed that shaft 29 is in an angular position with relation to guide 19 with which the same cooperates. Wheel 28 is in an oblique relation with plate 20, its portion nearest to the printing rollers 13 is at the nearest proximity to guard 21, as is best seen in Fig. 1, and it is further noted that wheel 28 is rotated into a counter-clockwise direction as viewed in Fig. 2, that is the upper portion of said wheel 28 rotates towards the printing rollers.

Affixed to guard 21 is an upwardly extending bracket 39, at the upper end of which bearing 40 is integrally formed. Journaled within said bear-

ing 40 is one end of shaft 41 which is in a transverse relation with guide 19. Supported by the opposite end of said shaft 41, which overhangs plate 20, is supporting lug 42. The lower end of said lug 42 is recessed, as at 43, wherein said shaft 41 is seated. Thumb-screw 44 passed through the rear end of said lug 42 is adapted to engage said shaft 41 for the purpose of maintaining said lug 42 in a rigid adjusted relation with said shaft 41. The upper end of said lug 42 is bifurcated for receiving therewithin the rear end of wheel supporting arm 45. Pin 46 passed through the upper end of said lug 42 and said arm 45 provides a pivot for the latter. The front end of said arm 45 is bent towards guard 21, and carries wheel 47. Said wheel 47 remains in contact with wheel 28 in the absence of a paper sheet therebetween. Rigidly affixed to arm 45 and substantially centrally thereof is threaded rod 48, which is in a parallel relation with arm 45 and directed rearwardly thereof. In threaded engagement with said rod 48 is weight 49.

From the hereinabove description it will be apparent that with relation to rod 48 pin 46 constitutes a fulcrum. When said weight 49 is shifted upon said rod 48 in the direction of front end of arm 45 and wheel 47 a greater degree of pressure of wheel 47 upon wheel 28 will be brought about than when said weight is shifted to the opposite direction. In fact when said weight 49 has been shifted to the very end of said rod 48 only a hardly perceptible degree of contact between wheels 28 and 47 will result.

Wheels 28 and 47 being in an oblique relation with plate 20, with their front portions in the nearest proximity to guard 21, when paper sheets shift upon plate 20 by being carried by conveyor chains 16 and pins 17, the right edge of the paper sheets will be received between said wheels 28 and 47. The oblique position of the said wheels with relation to plate 20 will cause the paper sheet to shift laterally and towards the adjacent guard 21 until the edge of the paper comes in contact with said guard 21. When that is accomplished further lateral shifting of the paper will be prevented by said guard 21, so that after that said wheels 28 and 47 will become inoperative for all intents and purposes, without however affecting the operativeness of conveyor chains 16 and pins 17. They will continue to carry the paper sheets towards the printing rollers, with the edges of the paper sheets in contact with guard 21, and without regard to said wheels 28 and 47.

When heavy or stiff paper is being fed to the printing rollers, it will require greater pressure between wheels 28 and 47 in order to shift its edge in contact with guard 21 than a thinner paper would require. Hence the regulation of the pressure between the said two wheels by the action of weight 49 as the same is shifted towards one or the opposite end of arm 45 and rod 48.

Although one pair of wheels 28 and 47 in cooperation with guide 19 would suffice to shift the adjacent edge of the paper sheets towards guard 21 and in contact therewith as the paper sheets are being fed to and between the printing rollers, if desired two or more pairs of said wheels 28 and 47 may be set up in cooperation with the same guide 19.

Although wheels 28 and 47 would suffice to bring the adjacent edge of the paper sheets in contact with guard 21, nevertheless, in order to assure the most efficient shifting of the paper sheets laterally in order that their edges may

come in contact with guard 21, before the paper sheets are received between the printing rollers, an auxiliary device for pushing the paper laterally towards one of said guards 21 is provided. Said device includes a plurality of feathers 50, each consisting of a comparatively thin resilient and oblong strip, soldered or otherwise rigidly affixed by one of its ends to the opposite guard 21. The free ends of said feathers 50 tend to spring away from guard 21.

Fastened to the upper face of plate 20 in guide 19 with which said feathers 50 are associated is cleat 51, which is positioned adjacent the free edge of said plate 20, and in a spaced relation with guard 21, as seen in Fig. 5. This cleat 51 has a double purpose. First, it confines the free ends of feathers 50 within the space defined by said guard 21 and said cleat 51, thereby preventing the free ends of said feathers 50 from springing beyond plate 20, and second, it prevents the paper sheet from falling below feathers 50, as the paper rides on top of said cleat 51. Thus said cleat 51 forms a guard preventing paper sheets from impinging between plate 20 and said feathers 50. In order that the paper sheets as they are carried towards the printing rollers may be supported upon a horizontal plane plate 20 of guide 19 with which said feathers 50 are associated should be upon a plane slightly below that of the opposite plate 20, just to the extent of the thickness of cleat 51 so that the paper resting upon cleat 51, conveyor chains 16 and the opposite plate 20 would rest upon a horizontal plane.

For preventing the paper sheets from shifting or curling by their adjacent edges above said feathers 50 a suitable guard is provided, consisting of a vertical bar 52, which overhangs cleat 51, and is in a spaced relation therewith and with the free ends of feathers 50, as is clearly seen in Fig. 5. Said bar 52 is maintained in a position by a plurality of supporting members 53 which are recessed at their upper ends for receiving rods 54. Thumb-screws 55 passing through the upper ends of said members 53 engage said rods 54 for rigidly maintaining said supporting members 53 and said bar 52 in a suspended relation with cleat 51.

The ends of said rods 54 are supported within the upper ends of standards 56 rigidly affixed to frame bars 10 and upwardly projecting therefrom. Of course, said rods 54 are disposed above rods 14 as well as above the paper carrying and supporting parts, including conveyor chains 16 and guides 19.

From the hereinabove description it will be readily seen that due to adjustability of brackets 22 and supporting members 53 upon rods 14 and 54, respectively, guides 19 may be shifted to or away from each other, with bar 52 shifted to conform to the adjusted position of the guide 19 with which the same coacts. The adjustability of these parts is desirable in order to fit the same to any particular width of the paper sheets fed towards the printing rollers.

As hereinabove indicated wheels 28 and 47 alone will be sufficient to shift the paper towards the adjacent guard 21 and in contact therewith. This equally holds true relative to feathers 50, because irrespective of wheels 28 and 47 feathers 50 alone are also sufficient to shift the edge of paper sheets in contact with the opposite guard 21. Therefore, these two devices may be used separately or together.

By means of the present device the adjustment

of the paper sheet transversely thereof or in a longitudinal relation with the printing rollers will be most accurate, because the paper sheet coming in contact with guard 21 can shift only in one, single, defined and predetermined path, that is the path charted by guard 21 with the side edge of the paper is in contact as the paper is fed towards the printing rollers.

It is further observed that when the present device is used in conjunction with the device disclosed in my said patent, which regulates or corrects the feed of the paper longitudinally of the course upon which the paper sheet travels towards the printing rollers, that is in a transverse relation with the paper rollers, the ultimate positioning of the paper sheets with relation to the printing rollers will be so accurate that the same paper sheet received between the printing rollers more than once will receive the printing impression in the same points, so that it would be not noticeable that the paper sheet has passed through the printing rollers more than once.

It is further noted that obviously wheels 28 and 47 may be positioned to the opposite direction, that is with their front portions facing or disposed towards the opposite guard 21. There would be no objection to such an arrangement provided that feathers 50 are eliminated from their association with said opposite guard 21. In that latter event the opposite side edge of the paper sheet would come in contact with said opposite guard 21, and the device would operate fairly well, particularly with heavier or stiffer paper sheets.

While there is described herein preferred embodiments of the present invention, it is nevertheless to be understood that minor changes may be made therein without departing from the spirit and scope of the invention as claimed.

What I claim as new is:

1. In a printing machine including printing rollers, means for positively advancing paper sheets directly toward the printing rollers in a direction at right angles to the axes of the printing rollers and a device for moving the advancing sheets into a desired position along the lengths of the printing rollers, said device comprising a guide including a horizontal plate and a vertical guard extending in a direction at right angles to the axes of the printing rollers, a first wheel, said plate being provided with a slot, said wheel partially entering said slot from below said plate, an arm pivotally supported by its rear end above said plate, a second wheel journaled at the front end of said arm, said second wheel being normally in contact with said first wheel, the contact point between said wheels being substantially on a plane coincident with the plane of the upper face of said plate, said wheels being in an oblique relation with said guard, portions of said wheels nearest to the printing rollers being in the nearer proximity of said guard than the remaining portions of said wheels, means for imparting a rotary movement to one of said wheels, paper sheets fed toward the printing rollers being received between said wheels for bringing one side edge of the paper sheets in contact with said guard prior to the reception of the paper sheets by the printing rollers, a rod secured to said arm at a point intermediate the front and rear ends thereof, said rod including a threaded portion extending substantially parallel to said arm from a point forwardly of said pivot point to a point rearwardly of said pivot point, and a weight in threaded engagement with said threaded portion

for movement axially thereof whereby said weight may be shifted upon said rod forwardly or rearwardly of said pivot point for increasing or decreasing the contactual pressure of said second named wheel upon said first named wheel.

2. In a printing machine including printing rollers, means for positively advancing paper sheets directly toward the printing rollers in a direction at right angles to the axes of the printing rollers and a device for moving the advancing sheets into a desired position along the lengths of the printing rollers, said device comprising a guide including a horizontal plate and a vertical guard extending in a direction at right angles to the axes of the printing rollers, a first wheel, said plate being provided with a slot, said wheel partially entering said slot from below said plate, an arm pivotally supported by its rear end above said plate, a second wheel journaled at the front end of said arm, said second wheel being normally in contact with said first wheel, the contact point between said wheels being substantially on a plane coincident with the plane of the upper face of said plate, said wheels being in an oblique relation with said guard, portions of said wheels nearest to the printing rollers being in the nearer proximity of said guard than the remaining portions of said wheels, means for imparting a rotary movement to one of said wheels, paper sheets fed toward the printing rollers being received between said wheels for bringing one side edge of the paper sheets in contact with said guard prior to the reception of the paper sheets by the

printing rollers, a rod secured to said arm at a point intermediate the front and rear ends thereof, a portion of said rod extending substantially parallel to said arm from a point forwardly of said pivot point to a point rearwardly of said pivot point, and a weight carried by said portion for movement axially thereof whereby said weight may be shifted upon said rod forwardly or rearwardly of said pivot point for increasing or decreasing the contactual pressure of said second named wheel upon said first named wheel.

3. Apparatus as defined in claim 2 wherein said means for positively advancing paper sheets directly toward the printing rollers comprises an endless chain extending in a direction at right angles to the axes of the printing rollers, and at least one pin mounted on said chain for engaging an edge of the paper sheets to be advanced to said printing rollers.
